UNITED STATES PATENT OFFICE

JAMES SPRUCE, OF WATERBURY, CONNECTICUT, ASSIGNOR TO SCOVILLE MANUFACTURING COMPANY, OF SAME PLACE.

IMPROVEMENT IN BELT-BUCKLES.

Specification forming part of Letters Patent No. **156,384**, dated October 27, 1874; application filed July 29, 1874.

To all whom it may concern:

Be it known that I, JAMES SPRUCE, of Waterbury, in the county of New Haven and State of Connecticut, have invented a new Improvement in Belt-Buckles; and I do hereby declare the following, when taken in connection with the accompanying drawings and the letters of reference marked thereon, to be a full, clear, and exact description of the same, and which said drawings constitute part of this specification, and represent, in—

Figure 1, front view; Figs. 2 and 3, the two parts detached; and in Figs. 4, 5, and 6, same views of a modification of the buckle.

This invention relates to an improvement in that class of buckles used to engage the two ends of a belt around the body of a person, the object being to lock the buckle when closed, so as to prevent its accidental disengagement; and it consists in providing the one part which overlaps the other with a hinged hook, which, when the two parts are set together, will engage a corresponding projection extending from the under part out through the overlapping part, as more fully hereinafter described.

A is the one part, and B the other, each provided with means for attachment to their respective ends of the belt, in the usual manner, the one part A has a raised central portion,

C, and the other part a similar form, D. When the two parts are set together, as in Fig. 1, the part C overlays the part D, as seen in Fig. 2^a, the shoulder *a* serving as a stop for the inner edge of the part D. On the part D is a stud or eye, F, which, when the two parts are set together, passes up through a corresponding perforation, L, in the part C. On the part C is hinged a hook, P, constructed to be turned to engage the stud F. This stud, as seen in Figs. 1 and 3, is grooved, as seen in broken lines, or formed with a head, and the hook slotted at *d*, to pass onto the stud, as seen in Fig. 1, the hook also forming an ornament on the front center of the buckle.

Instead of the stud, as in Figs. 1 and 3, it may be an eye, as in Figs. 4 and 5. In this case the hook will be provided with a tongue, *d*, as in Fig. 6.

I claim—

The herein-described buckle, composed of the two parts A C and B D, one of which has a perforation, L, and provided with a hinged hook, P, the other part constructed with an eye or stud, F, substantially as and for the purpose described.

JAMES SPRUCE.
